ROCKFORD, ILLINOIS, A CORPORATION OF ILLINOIS

METHOD OF AND MACHINE FOR RELIEVING CUTTERS

Application filed July 9, 1928. Serial No. 291,161.

The present invention relates generally to an improved method of and machine for forming and relieving spiral gashed formed cutters, such as hobs.

One of the objects of the present invention resides in the provision of a novel method and machine, by which hobs can be threaded and relieved in a single operation, and in such manner that the teeth can be sharpened repeatedly without altering the effective cutting contour.

On standard spiral gashed hobs, different points along the teeth do not lie in radial planes due to the fact that the teeth are identical to the teeth on straight gashed hobs, but are turned at a helical angle. This condition causes part of the contour to lie below an axial plane and the remainder to lie above said plane, there being only one point in the contour that is in a radial plane. If standard spiral gashed hobs are used to produce spline shafts having relatively wide flutes, the sides of the flutes will not be parallel. In ordinary practice, certain limits are specified for the hob, and the latter is formed by a cut and try method until one part of the tooth, for example the top, is near the maximum limit, while the other part of the tooth, for example the root, is near the minimum limit. This condition renders it difficult to obtain accurate work from spiral gashed hobs, it being especially noticeable in hobbing spline shafts where the spacing between the teeth of the hob is large. An important object of the present invention, therefore, resides in the provision of a method of and machine for forming and relieving the teeth of spiral gashed hobs by a molding-generating process in which a regenerated tool is used.

Another important object resides in the provision of a new and improved spiral gashed hob in which the teeth have a generated form so that all points in successive and adjacent edges are formed in helical lines about the circumference and when unwrapped from cylindrical position onto a plane are identical in shape to a form generated in a plane from a predetermined tooth shape.

A further object of the invention resides in the provision of a new and improved machine of the foregoing character which is automatic in operation, which is relatively simple and inexpensive in construction, and which is adjustable to adapt it to hobs of many different forms and sizes.

Another object of the invention resides in the provision of a method of forming and relieving spiral gashed hobs, such as spline shaft hobs, in which a regenerated lathe tool having a cutting face inclined at the same angle as the hob gashes, is caused to have a series of relative cyclic movements with a revolving hob blank, each movement comprising a cutting stroke and a free return stroke longitudinally of the blank, is caused to have a relative relieving movement once for each tooth transversely of the blank, is caused to have a gradual infeeding movement relative to the blank during successive cyclic movements until one end of the tool in a horizontal axial plane through the blank is cutting to the desired depth, is then caused to have a vertical feeding movement during successive cyclic movements to gradually elevate the cutting edge of the tool through said plane to generate the contour of the blank, and is given a relative compensating movement during the vertical feeding movement to compensate for the inclination of the hob gashes and to the lead of the hob contour.

A further object resides in the provision in a machine of the foregoing character of novel means for effecting a positive and accurate reversal in each cycle of movements so as to insure proper timing of the moving parts.

Still other objects reside in the provision in a machine of the above character of novel means for advancing the relieving reciprocations to compensate for the inclination of the teeth, and for advancing the traverse of the tool along the blank to compensate for the lead of the contour, during the vertical feeding movement.

Further objects and advantages will become apparent as the description proceeds.

In the accompanying drawings, wherein

I have illustrated the preferred embodiment of my invention:

Figure 1 is a plan view of the machine, certain parts being shown in horizontal section.

Fig. 2 is a fragmentary front view of the machine.

Fig. 3 is a fragmentary rear view of the machine.

10 Fig. 4 is a left end view of the machine as viewed in Fig. 2.

Fig. 5 is a fragmentary sectional view taken along line 5—5 of Fig. 2.

15 Fig. 6 is an enlarged sectional view of the main clutch mechanism taken along line 6—6 of Fig. 3.

Fig. 7 is a fragmentary vertical sectional view of a differential mechanism at the rear of the machine, taken along line 7—7 of Fig. 5.

20 Fig. 8 is a fragmentary sectional view taken along line 8—8 of Fig. 3.

Fig. 9 is a fragmentary sectional view of a differential mechanism at the front of the machine, taken along line 9—9 of Fig. 1.

25 Fig. 10 is a transverse vertical sectional view taken along line 10—10 of Fig. 1.

Fig. 11 is a view similar to Fig. 10, but showing the lathe tool withdrawn from the hob blank.

30 Fig. 12 is a fragmentary sectional view through a lathe tool and a work blank, diagrammatic in character, and showing the tooth generation of the spiral thread.

Fig. 13 is a plan view of one form of a 35 spline shaft hob adapted to be formed on the machine, and a lathe tool for forming and relieving the hob, the hob and lathe tool being shown in spaced relation.

Fig. 14 is a fragmentary perspective view 40 of the hob and the lathe tool at the start of the generating operation.

Fig. 15 is a view similar to Fig. 14, but showing the position of the lathe tool at an intermediate stage of the generating operation.

45 Fig. 16 is a view similar to Fig. 14, but showing the lathe tool at the end of the generating operation.

Fig. 17 is a diagrammatic view taken end- 50 wise of the hob blank illustrating the generating action resulting from elevating the lathe tool through the horizontal axial plane of the blank.

55 While the invention is susceptible of various modifications and alternative constructions, I have shown in the drawings and will herein describe in detail the preferred embodiment, but it is to be understood that I do not thereby intend to limit the invention to 60 the specific form disclosed, but intend to cover all modifications and alternative constructions falling within the spirit and scope of the invention as expressed in the appended claims.

65 Referring to the exemplary embodiment

of my invention illustrated in the drawings, the machine is adapted to form and relieve a large variety of cutters, and particularly spiral gashed hobs. In the present instance, the work blank is illustrated as a spline shaft hob 20. The hob is formed with a plurality of equally spaced and longitudinally inclined flutes or gashes 20^a defining a plurality of generally longitudinal blades 20^b, and with a single spiral groove 20^c intersecting the gashes 20^a at a large lead to define a thread of a plurality of hob teeth 20^d. It will be understood that while but a single thread is shown, the hob may be formed with any desired number of threads, i. e., may be a single or a multiple thread hob. The entire contour of the hob is formed in a molding generating process to be more fully described hereinafter, and hence all points along the contour are correctly formed and relieved.

70 A lathe tool 21, having the desired form, is provided for cutting the hob blank. In the present instance the lathe tool 21 has a distorted contour comprising a section 21^a adapted to form the groove 20^c and a section 21^b adapted to form the top of the hob teeth 20^d. The upper face of the tool 21 is inclined longitudinally of the hob at an angle corresponding to that of the gashes 20^a. It will be understood that the hob blank may be roughed in a preliminary operation before being accurately formed and relieved in the present machine, or may be formed completely in one machine operation as illustrated 80

85 90 95 100

Briefly stated, the operation comprises rotating the work blank 20 at a predetermined speed in a given direction, reciprocating the lathe tool 21 laterally of the blank once for each tooth to relieve the latter, traversing the lathe tool in a cutting stroke longitudinally of the work blank and in timed relation to the rotation thereof to generate the hob thread 20^d, separating the lathe tool and the work blank laterally of the latter after the completion of the cutting stroke and reversing the direction of rotation of the work blank and the direction of traverse of the lathe tool to return the latter in a free return stroke to its initial position, feeding the lathe tool into the work blank and repeating the foregoing cycle until the lathe tool is cutting the blank to the desired depth, then discontinuing the infeed of the lathe tool but continuing the foregoing cycle, gradually elevating the lathe tool to generate the desired contour during the last mentioned cycles, and advancing the relieving reciprocations and the rate of traverse of the lathe tool relative to the rotation of the work blank 110

115 120 125 130

135 during each cutting stroke so as to compensate for the inclination of the gashes 20^a and the spiral lead of the hob thread 20^d.

In the preferred embodiment, the machine 140 comprises a closed base 22 upon which the 130

other parts of the machine are mounted. These parts consist generally of a tailstock 23, a headstock 24, a cutting mechanism 25, a traversing mechanism 26, a relieving and free return mechanism 27 for reciprocating the lathe tool 21 laterally of the work blank 20 during each cutting stroke and for separating the lathe tool and the work blank during each return stroke, a control mechanism 28 for controlling the rotation of the lathe tool longitudinally of the work blank and the operation of the relieving and free return mechanism, a feeding mechanism 29 for elevating the lathe tool to generate the desired contour on the work blank, a relief compensating mechanism 30 for advancing the relieving reciprocations of the lathe tool relatively to the rotation of the work blank so as to compensate for the inclination of the gashes 20^a, and a generating compensating mechanism 31 for advancing the traverse of the lathe tool relative to the rotation of the work blank to compensate for the spiral lead of the hob thread 20^b.

25 *The tailstock*

The tailstock 23 (see Figs. 1, 2 and 3) comprises a bracket 32, which is secured to the base by any suitable means, such as the bolts 33, and which extends longitudinally along one end of the rear edge thereof. The bracket 32 is formed on its front side with dovetailed guideways 34 on which is adjustably mounted a tailstock slide 35 having a center supporting sleeve 36. A center 37, adapted to receive one end of a work supporting mandrel 38, is adjustably mounted in the sleeve 36, and is adapted to be adjusted by means of an adjusting knob 39.

60 *The headstock*

The headstock 24 (see Figs. 1, 2 and 3) comprises a housing or bracket 40 mounted on the base 22 opposite the tailstock 23, and secured in position by any suitable means, such as the bolts 41. The bracket 40 is formed with a pair of aligned bearings 42 and 43 supporting a work spindle 44. At its front end, the spindle 44 is formed with a suitable drive connection for the mandrel 38, such as a slotted head 45 for receiving an end key 46 on the mandrel.

For rotating the work blank, a large gear 47 is mounted on the spindle 44 and meshes with a small pinion 48 on a horizontal drive shaft 49. Of the drive shaft 49, one end is journaled in a suitable bearing 50 formed in a bearing bracket 51 which is secured by any suitable means, such as the bolts 52, to one end of the tailstock bracket 32, and the other end is journaled in a suitable bearing 53 in a bearing bracket 54 on the base 22.

Rotatably mounted on an enlarged portion 55 of the drive shaft 49 is a hollow cone pulley 56 which is adapted to be driven through

a belt 57 by any suitable power means (not shown). The small end of the pulley 56 is closed by a web 58, and the large end constitutes a housing for a planetary transmission adapted to connect the pulley to the drive shaft 49 through a reversing clutch 59.

The planetary transmission (see Fig. 6) comprises a plate 60 closing the large end of the pulley 56. A small gear 61 in the pulley 56 is rotatably mounted on the drive shaft 49 and is formed with an elongated hub 62 extending out of the pulley. The gear 61 meshes with two pinions 64 which are loosely rotatable on two diametrically opposed studs 65 extending inwardly from the plate 60. Rotatable respectively with the pinions 64 are two pinions 66 in mesh with opposite sides of a drive gear 67 keyed to the shaft 49. Preferably, the pinions 66 are fixed on hubs 68 on the pinions 64. To retain the double pinion members 64-66 on the studs 65, an annular retaining member 69 is provided having ears 70 secured to the free ends of the studs.

The clutch 59 (see Figs. 5 and 6) comprises an elongated sleeve 71 keyed to the hub 62 and secured to the outer face of the plate 60 by any suitable means, such as a retaining ring 72. A pair of lock-nuts 73 are threaded into locking engagement with each other onto the free or outer end of the sleeve 71. A pair of diametrically opposed notches 74 are cut into the sleeve 71 approximately midway of its ends. Slidably mounted on the sleeve 71 is a clutch sleeve 75. A pair of clutch cones 76 and 77 are secured respectively to opposite ends of the clutch sleeve 75. The clutch cone 76 is movable into and out of driving engagement with a clutch collar 78 which is rigidly secured to the cone pulley 56 and the plate 60 for rotation therewith, by any suitable means, such as the screw bolts 79. The clutch cone 77 is movable into and out of friction engagement with a clutch collar 80 which is similar to the collar 78 and which is rigidly secured by any suitable means, such as the bolts 81, to a circular plate 82 rigidly secured to the bracket 54. The plate 82 is formed with a central chamber 83 in which the lock-nuts 73 are disposed. A retaining ring 84 which is secured to the plate 82 projects in front of one of the lock-nuts 73 to aid in holding the sleeve 71 against axial movement.

Slidably mounted on the clutch sleeve 75 is a yoke sleeve 85 formed with an outer peripheral clutch groove 86. The sleeve 85 is provided with a pair of U-shaped key members 87 which project respectively into diametrically opposed slots 88 cut longitudinally in the sleeve 75 between the clutch cones 76 and 77 and constituting keyways. The length of the slots 88 is greater than that of the key members 87 so as to permit longitudinal movement of the yoke sleeve 85.

Pivotedly mounted intermediate their ends

on pivot pins 89 and within the slots 88 are two clutch fingers 90 having rounded ends 91. The ends of the key members 87 are cut away, as shown at 92 to provide cam surfaces for 5 engaging the rounded ends 91. Rounded lugs 93 on the fingers 90 project into the notches 74 to key the sleeve 75 to the sleeve 71. A pair of arcuate shoes 94 respectively engage opposite sides of the groove 86 and are 10 pivotally mounted on spaced arms 95 and 96 of a clutch yoke 97. The latter is pivotally mounted on a pin 98 for swinging movement on a bracket 99 rigidly secured to the end bracket 54. To provide means for 15 actuating the clutch 59, a lever 100 is secured to the pivot pin 98, and the free end of the lever is connected through a link 101 (see Fig. 2) to a hand lever 102 pivotally mounted at one end on a supporting stem 103.

20 *The cutting mechanism*

The cutting mechanism 25 (see Figs. 1, 10 and 11) comprises a main carriage 104 mounted for reciprocation on longitudinal ways 105 and 106 on the upper side edges of the base 22. The front edge of the carriage 104 is formed with an inwardly inclined depending flange 107 engaging a plate 108 on the underside of the way 105. The rear edge 25 of the carriage 104 is formed with a depending flange 109 secured on the way 106 by means of a gib plate 110. The carriage 104 is provided with an extension 111 having a threaded lug 112 (see Fig. 2) on its underside 30 and freely disposed in a channel 113 formed in the upper surface of the base 22. An adjusting or feed screw 114 engages the lug 112, and, upon rotation in opposite directions, is 35 adapted to feed the carriage in opposite directions longitudinally of the work blank 20.

To provide means for feeding the carriage 104 manually, one end of the feed screw 114 is provided with a bevel gear 115 meshing with a bevel gear 116 on a shaft 117. The 40 latter is journaled in a suitable bearing 118 formed on a bracket 119 secured to one end of the base 22, and is provided with a squared end 120.

Means is provided for driving the feed 50 screw 114 so as to feed the carriage 104 in predetermined relation to the rotation of the work blank 20. This means (see Figs. 1, 2, 4 and 9) preferably comprises a gear 121 on the work spindle 44 within the bracket 40, and 55 meshing at one side with a gear 122 on a shaft 123. The latter is suitably journaled in a bearing 124 formed in the bracket 40 and a bearing 125 formed in a bracket 126 at the left end of the base 22, and at its outer end 60 is connected through suitable speed change gears 127-128-129-130-131 to a short shaft 132. The speed change gears 128 to 130 inclusive are adjustably mounted on a segment arm 133 which is pivotally mounted on 65 the bracket 126 for adjustment about the

shaft 132 and which is adapted to be clamped in any position of adjustment by means of a suitable clamp bolt 134 extending through and adapted to engage an arcuate slot 135.

The shaft 132 (see Fig. 9) is journaled in 70 a bearing 136 formed in the bracket 126, and extends into an inner housing 137 of a differential mechanism 138. The inner housing 137 has a hub 139 rotatably disposed in the inner end of the bearing 136, and is disposed 75 in an outer housing 140 to which the bracket 126 is secured. The outer housing 140 is rigidly secured to the base 22 by any suitable means such as bolts 141 (see Fig. 2). The inner end of the shaft 132 is provided with a 80 bevel gear 142 in mesh at opposite sides with two bevel gears 143-144 pivotally mounted in the peripheral wall of the inner housing 137. The bevel gears 143-144 mesh with a bevel gear 145 on the end of the feed screw 85 114 journaled in a bearing 146 in the right end of the housing 140. The shaft 132 thus is adapted to drive the feed screw 114 through the housing 137.

Mounted in dovetailed guideways 147 (see 90 Fig. 2) on the carriage 104 for reciprocation laterally of the base 22 is a back-off or relieving slide 148. This slide is provided with transverse ways 149 supporting a side relief slide 150. Mounted for adjustment in transverse ways 151 on the slide 150 is a tool slide 152. Any suitable means may be provided for adjusting the slide 150, and in the present instance an adjusting screw 153 having threaded engagement with the tool slide 152 95 100 is provided. The front end of the screw 153 is rotatably journaled in an upstanding lug 154 formed on the front edge of the side relief slide 150. Mounted on the outer end of the screw 153 is a suitable hand wheel 155 105 and a micrometer sleeve 156.

The tool slide 152 is formed with vertical ways 157 in which a tool holder 158 is mounted for a vertical feed. To this end, the holder 158 is formed with a lug 159 in which is journaled a nut 160 having threaded engagement with an upstanding feed screw 161 journaled in the slide 152. The holder 158 is formed with a seat 162 to the underside of which the lathe tool 21 is adapted to be secured by 110 115 means of bolts 163.

The relieving and free return mechanism

Means is provided for reciprocating the lathe tool 21 laterally of the hob blank 20 and 120 in timed relation to the rotation thereof so as to properly relieve the hob teeth 20^a. This means (see Figs. 10 and 11) comprises a compression coil spring 164 tending to hold the cutting tool 21 out of engagement with the 125 hob. The spring 164 is positioned in a bore 165 formed in the backing-off slide 148, and extending from the front edge thereof to a central vertical bore 166 also formed in the slide. The front end of the bore 166 is closed 130

by a threaded plug 167 which is held in adjusted position by a lock nut 168, and which serves as an abutment for the front end of the spring. The inner end of the spring 164 is secured to a spring anchor 169 which is 5 formed on a stud 170 rigidly secured to the carriage 104.

The rear end of the backing-off slide 148 is formed integral with a rearward and upwardly inclined extension 171 having a pair of spaced arms 172—173 in which a stub shaft 174 is supported. Pivottally mounted intermediate its ends on the stub shaft 174 is a cam lever 175. A pair of hardened cam followers 176—177 are removably secured respectively to the upper and lower ends of the cam lever 175.

Securely but adjustably mounted on the carriage 104 at opposite sides of the cam lever 175 are a pair of spaced uprights 178—179. In the present instance, these uprights are secured in position by means of bolts 180, the heads of which engage a T-slot 181 formed in the rear edge of the carriage 104. The uprights 178—179 are formed respectively with upper alined bearings 182—183 and lower alined bearings 184—185.

A lower cam shaft 186 is journaled in the lower alined bearings 184—185, and supports 30 a rotary cam 187 adapted to coact with the cam follower 177. The cam 187 has a spiral working face 187^a terminating abruptly at 187^b, and is adapted upon rotation in a clockwise direction as viewed in Figs. 10 and 11, 35 to oscillate the lever 175 about the point of the cam follower 176 as a fulcrum to periodically give the cutting tool 21 a positive relieving movement toward the work blank 20. The cam follower 176 coacts with a rotary 40 cam 188 mounted on a shaft 189 rotatably and slidably disposed in the upper alined bearings 182—183.

The lower cam shaft 186 is operatively connected to the main drive shaft 49 to rotate the relieving cam 187 in timed relation to the rotation of the work blank 20. To this end, the shaft 186 is keyed for rotary movement in a spline sleeve 190 (see Fig. 3) which telescopes with and is splined for relative axial movement to a stub shaft 191. The latter is journaled in a hub 192 of a differential casing 193 (see Fig. 7), and is provided with a bevel gear 194 in the casing. The hub 192 is journaled in a bearing hub 195 formed 50 in a gear casing 196 rigid with a bracket 197 suitably secured to the rear side of the base 22. The bevel gear 194 meshes at opposite sides with two bevel gears 198—199 which are rotatably mounted on studs 200—201 fixed in opposite sides of the differential casing 193. The bevel gears 198—199 mesh 60 with a bevel gear 202 which is rotatable on a shaft 203 and which is formed integral with a drive plate 204. The drive plate 65 forms part of a ratchet mechanism 205

(see Figs. 5 and 7) which is operatively connected to the shaft 203 for rotating the shaft 186 in a counter-clockwise direction as viewed in Fig. 5, but not in the opposite direction.

The ratchet mechanism 205 comprises a 70 ratchet 206 which preferably is in the form of a ring, and is secured to the drive plate 204 by a central flange member 207 clamped in place by suitable screw bolts 208. The ratchet 206 is rotatably disposed within a 75 hollow cylindrical housing 209 which is keyed to the shaft 203 and one end of which is closed by the drive plate 204. While the ratchet 206 may be of any suitable form, preferably it is provided with a single peripheral tooth 210. Pivottally mounted on a pin 211 in a recess 212 in the peripheral wall of the housing 209 is a ratchet pawl 213 adapted to engage the tooth 210. The leaf spring 214 secured in the recess 212 engages 80 the movable end of the pawl 213 to hold the latter yieldingly in engagement with the periphery of the ratchet 206.

The shaft 203 is journaled in a bearing 90 216 formed in the bearing bracket 54 and carries a gear 217 on its outer end which is operatively connected through speed change gears 218—219 to a gear 220 on the outer end of the drive shaft 49. The gears 218—219 are adjustably mounted on a swing arm 95 bracket 221 embracing the bearing 53 and adjustable about the axis of the shaft 49. The swing arm bracket 221 has a slotted arcuate arm 222 adapted to be clamped in any position of adjustment by means of a bolt 100 223.

The cam 188 is adapted to position the backing-off slide 148 so as to hold the lathe tool 21 in operative relation to the hob blank 20 during each cutting stroke, and in inoperative relation thereto during each free return stroke. The cam 188 is substantially circular in form to provide a large arcuate cam surface 224. The end of this surface terminates abruptly in a notch 225 in the 110 periphery of the cam 188, and the lead side of this notch smoothly approaches said surface. Movement of the cam surface 224 into engagement with the cam follower 176 will oscillate the cam lever 175 about the 115 cam follower 177 as a fulcrum to move the slide 148 rearwardly against the force of the spring 164 to bring the tool 21 into operative relation to the blank 20, as illustrated in Fig. 10. Movement of the notch 225 into engagement with the cam follower 176 will 120 permit the latter to swing forwardly, thereby permitting the spring 164 to retract the tool 21 from the blank 20 into inoperative position, illustrated in Fig. 11.

The cam shaft 189 is splined to the cam 188, and one end is journaled in a suitable bearing 226 formed in the bearing bracket 51. The free end of the cam shaft 189 is 125 operatively connected through a ratchet

mechanism 227, not disclosed in detail but similar in construction to the ratchet mechanism 205, to a gear 228 on a shaft 229 which is suitably journaled in a bearing 230 in the bracket 54. The gear 228 is connected through reduction gears 231—232 to an idler gear 233 freely rotatable on the shaft 49, and meshing with the gear 121. The gears 231 and 232 are adjustably mounted on a supporting arm 234 on the bracket 51. It will be evident that by this construction, the gear 229 will be operative to drive the cam 188 in a clockwise direction as viewed in Fig. 10, but will be inoperative to drive the cam in a counterclockwise direction.

Means is provided whereby the side relief slide 150 may be given an automatic reciprocation for each relieving movement of the slide 148 so as to generate an oblique relief instead of a rectangular relief, when desired. This means (see Figs. 1 and 2) comprises a bracket 235 secured to the right end of the slide 148 and defining a lateral notch or guideway 236. A lever 237 is pivoted at one end in the bracket 235, and carries a roller 238 at one side of its pivot engaging the guideway 236. The lever 237 is formed with a longitudinal guideway 239 which is engaged by a stud 240 adapted to be adjustably mounted in a block 241 on the carriage 104. When the stud 240 is clamped in position on the block 241, reciprocation of the slide 148 will pivot the lever 237 about a fixed pivot, thereby causing the roller 238 to reciprocate the slide 150. The rectangular relieving components result in an oblique relief which is desirable when certain portions of the cutter contour are close to radial.

40 The control mechanism

Means is provided for automatically reversing the clutch 59 at opposite ends of the traverse of the cutting tool 21. With the 45 clutch in one position, i. e., to the right as viewed in Fig. 6, the hob 20 will be rotated downwardly against the lathe tool 21, the carriage 104 will be fed slowly in a cutting traverse to the left as viewed in Fig. 1, and the cams 187—188 will be rotated. With the clutch in the opposite position, the work 50 blank will be rotated in the opposite direction, the carriage 104 will be moved rapidly in a return traverse, and the cams 187—188 will be inoperative, the cam 188 being positioned as shown in Fig. 11 to provide clearance between the lathe tool and the hob.

The clutch reversing mechanism (see Figs. 1 to 5) comprises a rocker shaft 242 suitably journaled in a bracket 243 extending up from the bracket 54. The forward end of the rocker shaft carries a crank arm 244 having a pin 245 engaging in a notch 246 formed in an arm 247 on the clutch lever 100. As 60 the crank arm 244 is moved into either ex-

treme position, it serves to oscillate the lever 100 to reverse the clutch. Secured intermediate its ends to the rear end of the rocker shaft 242 is a lever 248 having outwardly projecting pins 249—250 at opposite ends. Rotatably secured on the rear end of the rocker shaft is a weight arm 251 on the free end of which a weight 252 is adjustably secured.

Means is provided for lifting the weight over dead vertical to cause the arm in the falling of the weight to strike one or the other of the pins 249—250 to reverse the clutch. Preferably this means comprises a spiral gear 253 rotatably mounted on the rocker shaft 242 and meshing with a spiral gear 254 on the shaft 229.

Formed on the rear face of the spiral gear 253 concentrically about the rocker shaft 242 is a ring 255. Two suitably spaced lugs 256—257 are formed on the end of the ring, 75 and abutment screws 258—259 are threaded therethrough for alternately engaging the weight arm 251 and lifting the latter over dead vertical upon rotation of the gear 253 in opposite directions.

Means is provided for throwing the clutch 59 into neutral at the end of each stroke of the carriage 104. This means comprises a rotary cam 260 having offset abutments 261—262 spaced about its periphery and adapted upon rotation of the shaft 229 in opposite directions to engage and move a pin 263, projecting from the yoke arm 96, in opposite directions. Preferably, the cam 260 has a limited rotational lost motion connection with the shaft 229 through a pin 264^a and slot 265^a, and is weighted to assume a predetermined position after each actuation of the clutch. By reason of this construction, the cam 260 need not turn a complete revolution with the shaft.

At the end of each cutting stroke, the abutment 262 will engage the pin 263 to open the clutch. Simultaneously, the weight 252 will have been carried over dead vertical by the abutment screw 258 so that the weight will fall, thereby closing the clutch in a direction to institute the free return traverse. At the end of each free return stroke, the abutment 261 will engage the pin 263 to open the clutch, and the weight 252 will have been carried over dead vertical by the abutment screw 259 so that it will fall to close the clutch in the opposite direction to institute the next cutting stroke.

110 Tool feeding mechanism

Means is provided for gradually elevating the lathe tool 21, during successive cutting cycles and after the latter has been fed into the blank to the desired depth so as to cause the effective cutting point of the tool in a horizontal axial plane through the blank to shift across the blank, thereby forming a correct and properly relieved generated con- 125

115

120

125

130

tour throughout the length of each blade 20^b. This means comprises a suitable drive for rotating the vertical feed screw 161. To this end, a worm 264 (see Figs. 7 and 8) is secured for rotation with the drive plate 204. The worm 264 meshes with a worm wheel 265 freely rotatable on a shaft 266 journaled on a bearing 267 on the bracket 197. The front face of the worm wheel 265 is formed with suitable clutch teeth 268 adapted to coact with similar clutch teeth 269 on a clutch member 270 splined to the forward end of the shaft. The clutch member 270 is formed with a peripheral groove 271 in which a bifurcated shifting yoke 272 is rotatably splined. The yoke 272 is connected to the rear end of a shifting rod 273 which is slidably disposed in a pair of spaced lugs 274 formed on the headstock bracket 40, and which is operatively connected at its front end to the depending arm of a clutch lever 275 pivotally mounted on a pin 275' supported in the bracket 40.

Secured to the rear end of the shaft 266 is a gear 276 which is connected through an intermediate speed change gear 277 to a gear 278 mounted on a shaft 279 journaled in the gear casing 196. The intermediate gear 277 is mounted on a carrier arm 280 pivotally secured on the bearing 267 for adjustment about the axis of the shaft 266, and adapted to be secured in adjusted position by means of a clamp bolt 281 engaging an arcuate slotted arm 282 thereon.

The shaft 279 is connected through spur gears 283—284 to a transverse shaft 285 extending to the front of the machine. Connected to the front end of the transverse shaft 285 is a spur gear 286 (see Figs. 1, 2 and 4) which is connected through an intermediate speed change gear 287 to a gear 288 on a shaft 289 journaled in a suitable casing 290 secured to the front of the base 22. A spiral gear 291 on the shaft 289 meshes with a spiral gear 292 on a feed shaft 293 extending longitudinally of the machine. The right end of the feed shaft 293 is connected through the flexible connection 294 to a shaft 295 which is journaled in and extends slidably through a pair of spaced bearings 296 formed on a tool slide 152. Splined to the shaft 295 is a gear 297 meshing with a gear 298 on a short shaft 299 journaled in the tool slide 152. The shaft 299 is provided with a suitable worm 300 which is operatively connected to the lower end of the feed screw 161 through a chain of gears 301—302—303 suitably arranged in a recess 304 in the underside of the tool slide.

Compensating mechanisms

As the lathe tool 21 is fed upwardly through the horizontal axial plane of the blank, the effective point on the cutting contour, cutting to maximum depth, gradually shifts from right to left. Due to the inclina-

tion of each blade 20^b, the cutting edge thereof advances as the cut to depth progresses along the blank. To compensate for the lead of the blades so that the effective cutting point on the lathe tool will meet each blade in a horizontal axial plane through the blank, means, designated for convenience as the relief compensating mechanism, is provided for advancing the relieving reciprocations in timed relation to the elevation of the tool. Preferably, the relief compensating mechanism comprises suitable gearing for driving the differential casing 193. To this end, (see Fig. 7) a worm 305 is provided on the shaft 279, and meshes with a worm wheel 306 preferably integral with the casing 193. It will be evident that when the clutch teeth 268—269 are in engagement to effect the vertical feed of the lathe tool 21, the differential casing 193 will be given a movement in addition to that imparted directly from the shaft 203 so as to accelerate the relieving reciprocations.

Due to the lead of the contour of the hob blank, an additional compensating movement is provided. To this end, means designated for convenience as the generating compensating mechanism is provided for accelerating the feed of the lathe tool 21 along the hob blank in timed relation to the vertical feed.

The generating compensating mechanism (see Figs. 1, 2, 4, 5 and 9) preferably comprises a driving connection between the feed shaft 293 and the inner differential casing 137. To this end, a spiral gear 307 is secured on the left end of the feed shaft 293, and meshes with a spiral gear 308 on a shaft 309 journaled in a bearing 310 formed on the differential casing 140. The outer end of the shaft 309 has a gear 311 which is connected through intermediate speed change gears 312—313 to a gear 314 mounted on a shaft 315 journaled in a bearing 316 formed in the differential casing 140. The intermediate speed change gears 312—313 are adjustably mounted on a swing arm bracket 317 which is mounted on the bearing 310 for pivotal adjustment about the axis of the shaft 309, and which has a slotted arcuate arm 318 adapted to be clamped in different positions of adjustment by a suitable clamp bolt 319. The shaft 315 (see Figs. 5 and 9) has a worm 320 meshing with a worm wheel 321 preferably formed integral with the differential casing 137. It will be evident that as the lathe tool 21 is elevated, the differential casing 137 will be given a movement in addition to that imparted from the shaft 132, thereby accelerating the feed of the carriage 104 to compensate for the lead of the blank contour.

Operation

The method will now be described in connection with the operation.

In setting up the machine for a given work blank, for example a hob with a right hand thread, the lathe tool 21 is adjusted vertically to position the highest point of the contour, designated as 322 (see Fig. 14), at or below a horizontal, axial plane through the work blank 20, and is positioned at the right end of the blank to start a cutting stroke toward the left. The face of the lathe tool 21 is inclined at the same angle as the flutes 20° , and hence the entire cutting contour of the tool will be below the horizontal, axial plane as indicated at *a* in Fig. 17. Due to the natural curvature of the work blank, the point in the cutting contour of the tool 21 in the axial horizontal plane, as indicated at *b* in Fig. 17, will cut to maximum depth, and other points of the contour above and below this plane at any time during the operation will recede from the cutter.

The clutch 59 is now actuated by means of the lever 102 to start the machine. In the operation, the cutter blank 20 is rotated forwardly at a predetermined speed, and the cam 187 gives the lathe tool 21 a relieving reciprocation in timed relation to the rotation of the blank so as to generate a spiral relief for each tooth. This relief may be radial or inclined depending upon whether or not the side relief mechanism is used.

The lathe tool 21 is given a cutting traverse to the left along the work blank in timed relation to the rotation of the latter to generate the lead of the hob contour, i. e., the groove 20° and the thread 20° . During the cutting traverse, the cam 188 is rotated slowly, but without influencing the position of the lathe tool.

The position of the parts is illustrated in Fig. 10. At the end of the cutting traverse, the cam 188 causes a separation of the blank and the tool, and the cam 260 accurately stops the foregoing operations by opening the clutch 59. The weight arm 251 then falls to reverse the clutch 59 to institute a free return movement for the lathe tool 21. During this free return movement the cams 187-188 are idle, and the rotation of the blank is reversed. The position of the parts is illustrated in Fig. 11.

At the end of the free return movement, the cam 260 again accurately opens the clutch 59, and the weight arm 251 again reverses the clutch, thereby actuating the cam 188 to return the lathe tool 21 into cutting engagement with the blank, and instituting a repetition of the foregoing cycle of operations.

At periodic times, preferably before the cutting stroke, the lathe tool 21 is given an incremental feed into the work. In the present instance, this feed is effected manually, but it is obvious that it may be effected in any suitable manner. When the lathe tool 21 has been fed into the blank to the desired depth, the infeed is discontinued. At this time, the

point 322 on the contour of the lathe tool is cutting to full depth and is properly relieving one point on the hob contour.

The generating operation is now instituted by actuating the lever 275 to close the clutch 268-269, thereby instituting a vertical feed for the lathe tool 21, a compensating movement for the relieving cam 187, and a compensating movement for the lathe tool longitudinally of the blank. The repeating cycle of movements is not affected and continues as before, it being understood that the vertical feed supplants the infeed.

During the generating operation, the lathe tool 21 thus is fed slowly in an upward direction to move the cutting contour of the tool through the horizontal axial plane of the blank. In the course of this feed, consecutive points along the cutting contour of the lathe tool will move successively into this plane, and then rise above the same as indicated at *c* in Fig. 17. As a result, the cut to depth proceeds along the contour of the blank. As the cut to depth proceeds, the relieving reciprocations are accelerated so that successive points along the inclined cutting contour of the hob will accurately meet the corresponding points on the lathe tool as the latter are elevated successively into the horizontal axial plane of the hob, and the cutting stroke of the tool is gradually advanced to compensate for the lead of the contour.

The hob thus is formed and relieved in a molding-generating operation, and when completed has a generated contour as shown in Fig. 12. The inclined cutting edges of the cutter or hob are so formed that like points in successive and adjacent edges are formed in helical lines about the circumference which, when unwrapped, will define a form identical to a form generated in a plane from a predetermined tooth shape. The hob thus will be correctly formed throughout the entire contour.

I claim as my invention:

1. A machine for relieving the teeth of cutters having cutting faces longitudinally inclined to the axis of the cutter and having a contour with a peripheral lead comprising, in combination, cutter rotating mechanism, a tool having a cutting edge longitudinally inclined to the axis of the cutter, means for relatively moving the cutter and tool transversely of the cutter axis to back off the teeth, means for relatively moving the cutter and tool tangentially of the cutter at the cutting point, and means for varying the action of said first mentioned means to compensate for the inclination of the faces and for relatively adjusting the cutter and the tool longitudinally of the cutter to compensate for the lead of the contour.

2. A machine for relieving cutters having cutting faces longitudinally inclined to the

- axis of the cutter and having a contour with a peripheral lead, comprising, in combination, cutter rotating mechanism, a tool having a cutting face longitudinally inclined to the axis of the cutter and having a cutting edge adapted to cut the desired contour, means for relatively moving the cutter and tool transversely of said axis during the passage of each tooth through the cutting plane, 5 means for passing the tool edge progressively through the cutting plane to transfer the point of operation on the cutter along said edge, and means for relatively adjusting said cutter and said tool longitudinally of said cutter to compensate for the lead of the cutter contour. 10
3. A machine for forming and relieving a work blank having generally longitudinal spiral gashes and a helical contour comprising, in combination, means for rotating the blank, a cutting tool having an inclined cutting face with a contour adapted to cut a predetermined contour, means for effecting a relative traverse between the blank and 20 said tool longitudinally of the blank, means for effecting a relative relieving reciprocation between the blank and said tool once for each tooth, means for effecting a tangential feed between the blank and said tool to move the 25 cutting edge of said tool through the cutting plane, means for accelerating the relieving reciprocation, and means for relatively adjusting the position of said tool longitudinally of the blank. 30
4. A machine for forming and relieving a work blank having generally longitudinal spiral gashes and a helical contour comprising, in combination, a cutting tool having a contour adapted to cut a predetermined contour and having an inclined face adapted to engage the blank in an axial cutting plane, 35 means for effecting a series of relative traverse movements between said tool and the blank longitudinally of the latter, means for effecting a relative relieving reciprocation between said tool and the blank, means for effecting a relative infeed between said tool and the blank in said axial plane, and means for effecting a relative tangential feed between 40 said tool and the blank to move different points along the cutting contour of the tool through said axial plane. 45
5. A machine for forming and relieving a work blank having generally longitudinal spiral gashes and a helical contour comprising, in combination, a cutting tool having a contour adapted to cut a predetermined contour and having an inclined face adapted to engage the blank in an axial cutting plane, 50 means for effecting a series of relative traverse movements between said tool and the blank longitudinally of the latter, means for effecting a relative relieving reciprocation between said tool and the blank, means for effecting a relative infeed between said tool and the blank in said axial plane, and means for effecting a relative tangential feed between 55 said tool and the blank to move different points along the cutting contour of the tool through said axial plane. 60
6. A machine for forming and relieving a work blank having generally longitudinal spiral gashes and a helical contour comprising, in combination, a cutting tool having a contour adapted to cut a predetermined contour and having an inclined face adapted to engage the blank in an axial cutting plane, 65 and the blank in said axial plane, means for effecting a relative tangential feed between said tool and the blank to move different points along the cutting contour of the tool through said axial plane, and means for varying the relieving reciprocation to compensate for the inclination of the blades during the tangential feed. 70
7. A machine for forming and relieving a work blank having generally longitudinal spiral gashes and having a helical thread intersecting said gashes comprising, in combination, means for rotating the work blank, a cutting tool having a cutting face inclined substantially the same as said gashes, means for effecting a relative relieving reciprocation between the blank and said tool in timed relation to the rotation of the blank, 75 means for effecting a continuous cycle of relative traverse movements between the blank and said tool longitudinally of the blank, means for separating the tool and the blank during each traverse movement in one direction, means for effecting a relative infeed between the tool and the blank, and means for effecting a relative tangential feed between the tool and the blank to transfer the final point of operation on the blank along 80 the edge of said tool. 85
8. A machine for forming and relieving a work blank having generally longitudinal spiral gashes and having a helical thread intersecting said gashes comprising, in combination, means for rotating the work blank, a cutting tool having a cutting face inclined substantially the same as said gashes, means for effecting a relative relieving reciprocation between the blank and said tool in timed relation to the rotation of the blank, 90 means for effecting a continuous cycle of relative traverse movements between the blank and 95 the edge of said tool. 100

said tool longitudinally of the blank, means for separating the tool and the blank during each traverse movement in one direction, means for effecting a relative infeed between the tool and the blank, means for effecting a relative tangential feed between the tool and the blank to transfer the final point of operation on the blank along the edge of said tool, and means for varying the timing of the 10 relieving reciprocation to compensate for the inclination of the gashes during the tangential feed.

9. A machine for forming and relieving a work blank having generally longitudinal spiral gashes and having a helical thread intersecting said gashes comprising, in combination, means for rotating the work blank, a cutting tool having a cutting face inclined substantially the same as said gashes, means 15 for effecting a relative relieving reciprocation between the blank and said tool in timed relation to the rotation of the blank, means for effecting a continuous cycle of relative traverse movements between the blank and said tool longitudinally of the blank, means for separating the tool and the blank during each traverse movement in one direction, means for effecting a relative infeed between the tool and the blank, means for effecting a 20 relative tangential feed between the tool and the blank to transfer the final point of operation on the blank along the edge of said tool, means for varying the timing of the relieving reciprocation to compensate for the inclination of the gashes during the tangential feed, and means for effecting a relative adjustment of said tool axially of the blank to compensate for the lead of the thread during 25 the tangential feed.

10. A machine for cutting rotary cutters having generally longitudinal spiral gashes and having a spiral groove intersecting said gashes to define hob teeth comprising, in combination, a main drive shaft, a reversing 30 clutch for said drive shaft, means connected to said shaft for rotating the cutter blank, a cutting tool, means operatively connected to said shaft for relatively traversing said tool longitudinally of said cutter, a relieving mechanism operatively connected to said shaft for effecting a relative relieving reciprocation between said tool and the cutter laterally of the latter once for each tooth, a separating mechanism operatively connected to said shaft for separating said tool and the cutter during each traverse in one direction, a cam operatively connected to said shaft for periodically opening said clutch, and means for automatically closing said clutch in the 35 reverse direction from which it was opened.

11. A machine for cutting rotary cutters having generally longitudinal spiral gashes and having a spiral groove intersecting said gashes to define hob teeth comprising, in combination, a main drive shaft, a reversing 40

clutch for said drive shaft, means connected to said shaft for rotating the cutter blank, a cutting tool having a contour adapted to cut the cutter contour and having an inclined cutting face, means operatively connected to said shaft for relatively traversing said tool longitudinally of said cutter, a relieving mechanism operatively connected to said shaft for effecting a relative relieving reciprocation between said tool and the cutter laterally of the latter once for each tooth, a separating mechanism operatively connected to said shaft for separating said tool and the cutter during each traverse in one direction, means for effecting an infeed of said tool relative to the cutter, means operatively connected to said shaft for effecting a relative tangential feed between said tool and the cutter, means operatively connected to said shaft for varying the timing of said relieving mechanism to compensate for the inclination of the gashes, means for adjusting said tool along said cutter to compensate for the lead of the groove, a clutch controlling the connection between said three last mentioned means to said shaft, a cam operatively connected to said shaft for periodically opening said clutch, and means operatively connected to said shaft, and operable to close said clutch in the reverse direction from which it was opened.

12. A machine for cutting rotary cutters having generally longitudinal spiral gashes and having a spiral groove intersecting said gashes to define hob teeth comprising, in combination, a main drive shaft, a reversing clutch for said drive shaft, means connected to said shaft for rotating the cutter blank, a cutting tool having a contour adapted to cut the cutter contour and having an inclined cutting face, means operatively connected to said shaft for relatively traversing said tool longitudinally of said cutter, a relieving mechanism operatively connected to said shaft for effecting a relative relieving reciprocation between said tool and the cutter laterally of the latter once for each tooth, a separating mechanism operatively connected to said shaft for separating said tool and the cutter during each traverse in one direction, a cam operatively connected to said shaft for periodically opening said clutch, means driven in timed relation to said cam for automatically closing said clutch in the reverse direction from which it was opened, means interposed in the connections between said shaft on one hand and said relieving mechanism and said separating mechanism on the other hand for preventing reversal of movement of said mechanisms.

13. A machine of the character described comprising, in combination, a main drive shaft, a reversing clutch for said shaft, a reciprocatory element, means operatively connected to said shaft for driving said element,

5 a cam operatively connected to said shaft and rotating in timed relation to the movement of said element, said cam being operative to open said clutch so as to stop movement of said element in either direction, a pivotal weight adapted upon movement in opposite directions over dead vertical to close said clutch in opposite directions, and means driven in timed relation to said cam for alternately moving said weighted member across dead vertical immediately prior to opening of said clutch by said cam, said weighted member upon falling serving to throw said clutch in the opposite direction.

15 14. A machine of the character described comprising, in combination, a main drive shaft, a reversing clutch for said shaft, a reciprocating element, means operatively connected to said shaft for driving said element, 20 a cam shaft operatively connected to said shaft, a cam on said cam shaft for opening said clutch at predetermined points in the travel of said element, a pivotal weighted member adapted upon movement in opposite directions over dead vertical to fall so as to close said clutch in opposite directions, and means operatively connected to said cam shaft for alternately lifting said weighted member in opposite directions across dead 25 vertical immediately prior to opening of said clutch by said cam.

15. The method of relieving the teeth of a cutter having cutting faces longitudinally inclined to the axis of the cutter and having 30 a contour with a peripheral lead, which consists in backing off said teeth by relative backing off movements between the rotating cutter and a tool having a cutting face longitudinally inclined to the axis of the cutter, moving the cutting edge of said tool tangentially of the cutter to move the latter through the cutting plane, and relatively adjusting said tool along the cutter to compensate for the lead of the cutter contour.

45 16. The method of relieving the teeth of a cutter having cutting faces longitudinally inclined to the axis of the cutter and having a contour with a peripheral lead, which consists in backing off said teeth by relative 50 backing off movements between the rotating cutter and a tool having a cutting face longitudinally inclined to the axis of the cutter, moving the cutting edge of said tool tangentially of the cutter to move the latter through the cutting plane, relatively adjusting said tool along the cutter to compensate for the lead of the cutter contour, and varying the relieving movement of the tool relative to the cutter to compensate for the inclination of the 55 faces.

17. The method of forming and relieving a work blank having generally longitudinal spiral gashes and having a helical thread intersecting said gashes consisting of rotat- 60 ing the work blank, effecting a relative re-

lieving reciprocation between the blank and a tool having an inclined cutting face, effecting a continuous cycle of relative traverse movements between the blank and said tool longitudinally of the blank, separating the 70 tool and the blank during each traverse movement in one direction, effecting a relative infeed between the tool and the blank, then effecting a relative tangential feed between the tool and the blank to transfer the 75 final point of operation on the cutter along the edge of said tool, varying the relieving movements to compensate for the inclination of the gashes during the tangential feed, and effecting a relative adjustment of said tool axially of the blank to compensate for the 80 lead of the thread during the tangential feed.

18. A machine of the character described comprising, in combination, a drive shaft, a reversing clutch for said shaft, a reversible 85 element, means operatively connected to said shaft for driving said element, a cam shaft operatively connected to said drive shaft, a cam on said cam shaft for opening said clutch at predetermined points in the travel of said 90 element, a pivotal member adapted upon movement in opposite directions past dead center to close said clutch in opposite directions, and means operatively connected to said cam shaft for alternately moving said 95 pivotal member in opposite directions across dead center immediately prior to opening of said clutch by said cam.

19. A machine of the character described comprising, in combination, a drive shaft, a 100 reversing clutch for said shaft, a reversible element having a drive connection with said shaft, means operable at a predetermined point in the travel of said element in each direction to open said clutch, a reversible trip 105 member adapted upon movement in opposite directions past a predetermined point to close said clutch, and means operable in timed relation with said last mentioned means for alternately moving said trip member in opposite directions past said last mentioned predetermined point.

20. A machine of the character described comprising, in combination, a drive shaft, a reversing clutch for said shaft, a reversible 110 element having a drive connection with said shaft, means operable at a predetermined point in the travel of said element in each direction to open said clutch, a pivotal weighted member adapted upon movement 115 in opposite directions over dead vertical to fall so as to close said clutch selectively in opposite directions, and means operatively connected to said last mentioned means for alternately lifting said weighted member in 120 opposite directions across dead vertical immediately prior to each opening of the clutch.

In testimony whereof, I have hereunto affixed my signature.

JOHN EDGAR. 130
